(57) **CLAIM**

The ornamental design for a storm door with light, as shown and described.

DESCRIPTION

FIG. 1 is a perspective view of a storm door with light showing the new design.

FIG. 2 is a rear view of the storm door with light of FIG. 1. FIG. 3 is a front view of the storm door with light of FIG. 1.

FIG. 4 is a side view of the storm door with light of FIG. 1. FIG. 5 is an opposite side view of the storm door with light of FIG. 1.

FIG. 6 is a top view of the storm door with light of FIG. 1. FIG. 7 is a bottom view of the storm door with light of FIG. 1.

FIG. 8 is an unobstructed perspective view of the storm door with light of FIG. 1.

FIG. 9 is an unobstructed rear view of the storm door with light of FIG. 2.

FIG. 10 is an unobstructed front view of the storm door with light of FIG. 3.

FIG. 11 is an unobstructed side view of the storm door with light of FIG. 4.

FIG. 12 is an unobstructed opposite side view of the storm door with light of FIG. 5.

FIG. 13 is an unobstructed top view of the storm door with light of FIG. 6; and,

FIG. 14 is an unobstructed bottom view of the storm door with light of FIG. 7.

All of the broken lines in the accompanying drawings illustrate environmental structure and form no part of the claimed design.
